Edgar Gatehouse

UNITED STATES PATENT OFFICE.

ALFRED W. FLETCHER, OF BROOKLYN, NEW YORK.

SUBMERGIBLE HEATER.

1,413,268.

Specification of Letters Patent. Patented Apr. 18, 1922.

Application filed August 16, 1921. Serial No. 492,688.

To all whom it may concern:

Be it known that I, ALFRED W. FLETCHER, a citizen of the United States, and residing at Brooklyn, in the county of Kings and 5 State of New York, have invented certain new and useful Improvements in Submergible Heaters, of which the following is a specification, such as will enable those skilled in the art to which it appertains to 10 make and use the same.

This invention relates to what are known as submergible heaters, and the object thereof is to provide a device or apparatus of this class which is designed primarily for 15 use in heating water in bath tubs; and a further object being to provide an improved device of this class which is simple in construction, efficient in operation and which may also be used for heating water in vessels or 20 receptacles other than bath tubs and for any desired purpose, and with these and other objects in view the invention consists in a device or apparatus of the class specified, constructed and operated as hereinafter 25 described and claimed.

The invention is fully disclosed in the following specification, of which the accompanying drawing forms a part, in which the 30 separate parts of my improvement are designated by suitable reference characters in each of the views, and in which:—

Fig. 1 is a sectional side view of a bath tub and indicating the use of my improved submergible heater;

Fig. 2 a plan view of the heater removed from the bath tub;

Fig. 3 a section on the line 3—3 of Fig. 2; and,

Fig. 4 a side view at right angles to that 40 of Fig. 1 with part of the construction broken away.

In the drawing forming part of this specification, I have shown an ordinary bath tub *a* provided with the usual water supply 45 faucets *a*², only one of which is shown, and a drainage outlet *a*³ and, in the practice of my invention, I provide a submergible heater *b* which is adapted to be placed in the bath tub, and, in the construction shown, 50 to rest on the bottom thereof.

The main part of the heater consists of a bottom or body part *c*, which for the purpose of this description, will be called a water heater or boiler, and this boiler, in 55 the construction shown, is composed of sheet metal and is rectangular in form being

square or approximately so, and said boiler comprises a top *c*², a bottom *c*³ and, in the construction shown, four similar sides *c*⁴. Within the boiler are placed water circulating tubes *d* which, in the construction shown, 60 are arranged in three separate layers one above another, the middle layer being at right angles to the top and bottom layers.

In the bottom portion of the boiler and resting on the bottom thereof, in the construction shown, is a gas burner *e* composed of top and bottom plates secured together by screws or bolts *e*², and in the perimeter of which is a complete annular row of gas outlets *e*³ and secured centrally in the top of the burner *e* is a tube *f* which passes upwardly through the boiler, through the top thereof, and connected with the top of the tube *f* is a Bunsen burner coupling *g*, which 70 is provided with air inlets *g*² in the sides thereof, and in the top of which is secured a nozzle member *g*³ in the bottom portion of which is a valve device *g*⁴ above which is a pilot burner coupling attachment *g*⁵ 80 provided with a valve *g*⁶ and with a pilot burner tube *g*⁷.

It will be understood that the water circulating tubes *d* extend entirely through the boiler and are open at both ends, and at the 85 opposite sides of the boiler and centrally thereof, in the construction shown, are vertical air inlet members or tubes *h*, four of which are employed, in the construction shown, and these air inlet members or tubes 90 are secured to the boiler and extend downwardly on the outer sides thereof to the bottom portion thereof where they communicate with the boiler, or the interior thereof, through ports or passages as shown at *h*². 95

Secured in the top *e*² of the heater body or boiler are flue pipes *i* three of which are shown, and the pilot burner tube *g*⁷ communicates with one of these flue pipes as clearly shown.

In the construction shown both the air inlet members or tubes *h* and the flue pipes *i* extend a predetermined distance above the top of the heater body or boiler *b* and the flue pipes *i* and project or extend above the 105 air inlet members or tubes *h*, and this construction or arrangement facilitate the operation of the device or apparatus as hereinafter described.

The nozzle member *g*³ is provided with 110 the usual reduced and ribbed or corrugated nozzle *g*⁸ with which in the use of the de-

vice is connected a flexible tube *j* by which gas is supplied to the burner *e*, and the operation of my improved submergible heater will be understood from the foregoing description taken in connection with the following statement.

In practice, or when it is desired to heat water in the tub *a*, the heater is placed in the tub as shown in Fig. 1, and water is admitted to the tub until it covers the top of the heater body or boiler, as indicated in said figure, after which the valve *g*⁶ is opened and the gas passing through the pilot burner tube *g*⁷ and discharged into the top of the flue pipe *i* is ignited, after which the valve device *g*⁴ is opened and gas passes down through the Bunsen burner coupling *g* in which air entering through the air inlets *g*² is mingled therewith and the mingled 10 gas and air passes down through the tube *f* into the burner *e*, and this mingled gas and air rises to the body portion of the boiler or heater and is ignited by the flame of the pilot burner tube *g*⁷ as will be readily understood.

It will be observed that the heater body or boiler *c* is made somewhat in the manner of an ordinary tubular boiler, and the water in the tub is free to circulate through all of the tubes *d*, and the result of this operation is the quick heating of the water in the bath tub to the desired extent, after which the flow of gas into the burner *e* is cut off and the submergible heater removed from the bath tub. It will be understood that when the gas and air escaping from the burner *e* is ignited, as hereinbefore described, the valve *g*⁶ of the pilot burner tube *g*⁷ is closed and the flue pipes *i* carry off the products 20 of combustion arising from the burner *e* in the operation of the device, as hereinbefore described.

With my improved submergible heater, a small amount of water may be first heated 25 to a high degree, after which the heater may be removed from the tub and cold water added to, or permitted to flow into the tub until the tub is filled to the desired extent, and the temperature of the water there- 30 in reduced to the degree required for bathing purposes, but my invention is not limited to any particular height of the air inlet tubes or members *h*, or the flue pipes *i*, and the apparatus may be so made that the 35 amount of water required for a bath may be all heated at one time up to the required degree, and it will thus be seen that my invention is not limited to the exact construction herein shown and described, nor to any 40 particular method or process of using the same, and while I have shown and described the preferred form of my improved submergible heater, it will be understood that my invention is not limited to the number or 45 arrangement of the water circulating tubes

d, nor to the position in which they are placed in the body portion of the heater or boiler, nor to any particular means for supplying air to the burner *e*, nor to any particular form of said burner, and while I have shown said burner as resting on the bottom of the boiler, this is not necessary and said burner may be supported entirely by the tube *f* or in any other way, and it will also be noted that while I have shown the body portion or boiler of my improved submergible heater as without independent supports and as resting on the bottom of the tub when in use, this is also not necessary, and said boiler may be provided with means whereby it will be supported above the bottom of the tub, if desired, and changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. A submergible heater of the class described comprising a body portion or boiler, a burner device mounted in the bottom part of said body portion or boiler, means for supplying gas and air to said burner device, means for supplying air to the bottom part of the body portion or boiler, means for permitting the escape of the products of combustion from said body portion or boiler, and a plurality of water circulating tubes extending transversely through said body portion or boiler and one above another.

2. A submergible heater comprising a body portion or boiler having a disk-shaped burner in the bottom thereof, a gas and air supply tube passing upwardly through the top of the body portion or boiler and communicating with said burner, a gas and air supply device connected with the top of said supply pipe, water circulating tubes arranged within the body portion or boiler and extending transversely therethrough one above another and open at both ends, means for supplying air to the bottom part of the body portion or boiler and escape flues connected with the top thereof.

3. In a submergible heater, a body portion or boiler, provided with water circulating tubes which extend therethrough and which are open at both ends, a gas and air supply tube mounted vertically in said body portion or boiler and passing through the top thereof and extending thereabove and downwardly into the bottom part of the body portion or boiler, a gas burner device in the bottom part of the body portion or boiler and with which said gas and air supply tube communicates, means for supplying gas and air to said tube, means for sup-

plying air to the bottom part of the body portion or boiler, escape flue pipes connected with the top of the body portion or boiler, and a pilot burner device communicating with the top portion of one of said flue pipes.

4. In a submersible heater, a body portion or boiler provided with water circulating tubes arranged in tiers and which extend therethrough and which are open at both ends, a gas and air supply tube mounted vertically in said body portion or boiler and passing through the top thereof and extending thereabove and downwardly into the bottom part of the body portion or boiler, a gas burner device in the bottom part of the body portion or boiler and with which said gas and air supply tube communicates, means for supplying gas and air to said tube, means for supplying air to the bottom part of the body portion or boiler, and escape flue pipes connected with the top of the body portion or boiler.

5. A submersible heater comprising a body portion or boiler provided with water circulating tubes passing therethrough and open at both ends, a gas supply tube mounted in the top of the body portion or boiler and extending above said top and downwardly into the bottom part of the body portion or boiler and communicating at its lower end with a burner, a gas and air inlet device connected with and communicating with the top of said supply tube, air inlet devices connected with the sides of the body portion or boiler and communicating with the bottom part thereof, and flue pipes connected with the top of the body portion or boiler and communicating therewith and extending a predetermined distance above the top thereof.

6. A submersible heater comprising a

body portion or boiler provided with water circulating tubes passing therethrough and open at both ends, a gas supply tube mounted in the top of the body portion or boiler and extending above said top and downwardly into the bottom part of the body portion or boiler and communicating at its lower end with a burner, a gas and air inlet device connected with and communicating with the top of said supply tube, air inlet devices connected with the sides of the body portion or boiler and communicating with the bottom part thereof and extending above the top thereof, flue pipes connected with the top of the body portion or boiler and communicating therewith and extending a predetermined distance above the top thereof, and a pilot burner tube connected with the gas and air supply device and communicating with one of said flue pipes.

7. A submersible heater of the class described comprising a box-shaped casing, a burner device mounted centrally of the bottom portion of the casing, means for supplying gas and air to said burner device, means at the sides of said casing for supplying air to the bottom portion of said casing, means in the top of said casing for permitting the escape of the products of combustion therefrom, and a plurality of tubes mounted transversely of the casing in two directions and opening outwardly through the sides thereof and through which water is adapted to be circulated.

In testimony that I claim the foregoing as my invention I have signed my name in presence of the subscribing witnesses this 15th day of August, 1921.
